his ATTORNEY.

UNITED STATES PATENT OFFICE.

AARON H. WOLFF, OF NEW YORK, N. Y.

GAS HEATER.

1,410,236.

Specification of Letters Patent. Patented Mar. 21, 1922.

Application filed March 8, 1921. Serial No. 450,622.

To all whom it may concern:

Be it known that I, AARON H. WOLFF, a citizen of the United States, residing at the borough of Manhattan, in the city, county, and State of New York, have invented certain new and useful Improvements in Gas Heaters, of which the following is a specification, reference being had therein to the accompanying drawings, which form a part thereof.

My invention relates to gas heaters, and more particularly to a device of this character particularly adapted for domestic use.

In a heater made in accordance with my invention, the construction is such as to ensure the effective utilization of the heat from the burners in raising the temperature of a large volume of circulating air and its diffusion about the room to be heated, thus securing economy in the operation of the heater.

The construction by which the desired circulation of air is secured is also effective in cooling the metal at the back of the heater, and that portion of the upper part of the reflector which is subjected to the highest temperatures while the heater is in use.

The gas burners are so constructed as to ensure substantially complete combustion of the gas, the products of combustion being commingled with the moving air and delivered therewith into the room to be heated, these heated gases delivered adjacent the outlet increasing the effective movement of air in the air circulation system and also inducing an up-draft adjacent the top of the burners and the heating elements associated therewith, from the front of the heater or adjacent the casing or reflector.

By reason of the cooling effect of the moving air upon the metallic portions of the heater at the back thereof, high temperatures may be developed by the heating unit without likelihood of injury to inflammable matter near the back of the heater, and the heater while in operation may be readily transported from place to place by means of a handle carried by the cooled back structure of the heater.

The casing or reflector structure at the front of the heating unit projects radiant heat into the room in the same manner as the reflectors now ordinarily used in gas

heater embodying therein a reflecting casing having an opening substantially centrally thereof, whereby a reflecting surface is presented about and in front of said opening, means forming a combustion chamber rearwardly of said opening, a heating unit within said combustion chamber and exposed through said opening, and means forming a flue, the opposite ends of which communicate respectively with atmosphere adjacent the lower part of and above, said combustion chamber, whereby a convection movement of air is set up about said combustion chamber and air so heated is delivered to a room; and in such other novel features of construction and combination of parts as are hereinafter set forth and described, and more particularly pointed out in the claims hereto appended.

Referring to the drawings,

Fig. 1 is a front view of a heater embodying my invention;

Fig. 2 is a section on the line 2—2 of Fig. 1; and

Fig. 3 is a section on the line 3—3 of Fig. 2.

Like letters refer to like parts throughout the several views.

In the embodiment of my invention shown in the drawings, *a* indicates a casing which is preferably of polished copper or other suitable material to form a reflector for projecting radiant heat forwardly of the heater. This casing reflector, substantially centrally thereof, has a rectangular opening *a'*, therethrough, rearwardly of which is a housing *b* forming a combustion chamber above the gas burner *c*, which is of the blue-flame type and has associated therewith a plurality of refractory elements *d* known in the art as radiants, positioned within said combustion chamber, one above each burner opening.

The housing *b* of the combustion chamber may be of any desired construction, that ordinarily employed being a solid sheet metal back plate, a perforated sheet metal front plate and an interposed sheet of asbestos. This construction being immaterial to the invention, is shown merely conventionally in the drawings.

The open front of the casing *a* is protected by a shield *a'* which may be of any desired construction.

At the rear of the casing *a* and the back wall of the housing of the combustion cham-

ber *b*, I provide means forming a flue *e* the opposite ends of which respectively communicate with atmosphere adjacent the lower part of the combustion chamber or 5 housing *b* and above said housing, said flue forming means inclosing the combustion chamber with the two-fold object of cooling the wall of the combustion chamber and the upper part of the casing *a*, and utilizing the 10 heat transferred from said wall and said casing to induce a convection movement of air which will be delivered into the room adjacent the top of said casing *a*.

The rear wall of said flue forming means 15 *e* extends parallel with the back wall of the housing of the combustion chamber *b*, and then forwardly across the top of said combustion chamber and the top of the casing so as to direct the heated air passing from said 20 flue substantially horizontally, and thus ensure a more effective diffusion of the heated air emitted from said flue.

The combustion chamber *b* opens into said flue adjacent the top thereof, thus delivering 25 the products of combustion into the flowing stream of heated air, raising the temperature thereof so as to increase the rate of flow of this air through the flue, and at the same time inducing a movement of 30 air through the upper portion of the opening *a'*. This will increase the effective volume of secondary air for ensuring a complete combustion of the mixture of gas and primary air at the burner openings, and 35 about the radiants or refractory elements. By reason of the air gap between the back wall of the housing *b* and the rear wall of the flue *e*, and the continuous and fairly rapid movement of air through said flue, the 40 back wall of the flue will never become so heated as to endanger any object closely adjacent thereto, and at the same time the use of the handle *f* in transporting the heater from one place to another in a room while 45 it is in operation, is permitted, said handle being secured to the upper rear wall of the flue *e*.

The burner *c* consists of a mixing chamber 50 having a plurality of aligned openings *c'* at the top thereof and a plurality of openings at the bottom thereof in axial alignment with said top openings, but of smaller diameter. Passing vertically through the burner casing are a plurality of supplemental air tubes 55 *c*² which open through the lower openings in said casing and through the burner openings *c'* thereof, being substantially co-terminous with the tops of said last named openings and of a sufficiently small diameter 60 to afford burner jet openings about the tubes and concentric therewith. At one side of the tubes *c*² is an enlarged portion *c*³ extending adjacent all of the said tubes *c*², the purpose of which enlarged portion is to 65 form a distributing chamber which will en-

sure substantial uniformity in the volume of gas and air mixture delivered to each of the burner openings *c'*.

Discharging into the chamber *c*³ is a mixing tube *g* provided with the usual valve 70 controlled nipple *g'* by means of which the burner may be connected with a source of gas supply.

The mixing tube *g* discharges directly into the distributing chamber *c*³, the relation 75 of the outlet of said tube and the various supplemental air tubes *c*² being such as to provide an unobstructive passage between said outlet and said distributing chamber.

The heater is provided with any desired 80 form of base *h*.

Supported from the top of the burner *c* is a plate *i* having webs *i'* thereon for positioning the refractory elements or radiants with relation to the various burner openings *c'*. 85 This plate projects rearwardly of the housing *b* into engagement with the back wall of the flue *e* and is of a width to engage both side walls of said flue. The portion of said plate within said flue is provided with a plurality of openings *i*² to permit the passage of air therethrough.

The portion of the plate *i* extending into engagement with the walls of the flue serves merely as a stay for the flue at this point, 95 and may be dispensed with if desired.

A suitable opening in the back wall of the flue *e* is provided at *e'* to accommodate the mixing tube *g*.

The outlet of the flue *e* is provided with 100 a protecting gauze or screen *j* used largely to secure a better finish in the commercial article.

The operation of the herein described heater is substantially as follows:— 105

When gas is delivered to the burner through the mixing tube *g*, it will pass directly to the distributing chamber *c*³ in which it will be diffused for the entire width of the burner so as to flow in substantially equal volume and at substantially uniform pressure to each of the burner openings *c'*. This result can be secured only by having the gas and primary air mixture flow directly into said distributing chamber 110 through an unobstructed path, since if the mixture should impinge upon any of the tubes *c*², the opening *c'* adjacent said tube would receive too great a volume of the mixture and the remaining burner openings would receive too small a volume, or if the volume of inflowing mixture be reduced to properly proportion the volume thereof delivered to a particular burner, the volume delivered to the other burners would be sufficiently 115 reduced to produce a very marked difference in the flame at the different burners.

After the burner has been lighted for a short interval, the various refractory elements or radiants *d* will become incandescent 130

as a result of the action of the blue flame of the various burner openings thereon.

As the air in the flue *e* adjacent the housing *b* is heated, a convection movement of air will be set up in said flue, which will be augmented by the escape of the products of combustion through the open top of the housing *b* into said flue at a point intermediate the inlet and outlet thereof. In this 10 manner a continuous stream of heated air will be projected substantially horizontally into a room, the volume of this air, by reason of the arrangement of the flue *e*, being very much greater with a given consumption of 15 gas than would normally be heated in the absence of said flue.

The upflow of the products of combustion in addition to increasing the volume of air moving through the flue *e*, will also induce 20 a movement of air from the front of the housing *b* through the combustion chamber, thus increasing the effective supply of secondary air, ensuring perfect combustion of the gases within and about the refractory 25 elements, and avoiding the presence of noxious fumes discharged from the flue into the room.

The polished surface of the casing *a* will 30 project radiant heat forwardly of the heater, supplement the pleasing effect of the refractory elements or radiants, and more or less control the flow of air through the opening *a'* to the combustion chamber, particularly toward the lower part thereof.

35 The arrangement of the casing *a* and of the outlet of the flue *e* will cause the entire volume of air heated to be projected forwardly of the heater in a manner to secure a very effective diffusion thereof toward the 40 lower part of a room, the entire back of the heater being kept at a fairly low temperature by the air circulating through the flue *e*. The presence of the flue adjacent the portion of the casing *a* directly above and in front 45 of the housing *b* will reduce the temperature of this portion of the casing in a manner to prevent a rapid tarnishing thereof, although it will be necessary from time to time to polish this portion of the casing.

50 While preferably the inlet of the flue *e* is extended well below the burner openings *c'*, this is not essential, since it is merely necessary to have the inlet of the flue communicate with atmosphere adjacent the said 55 burner openings, the construction shown being largely for securing a better finish in the product, since the flue conceals the entire burner structure from the back and sides, the casing *a* concealing it from the 60 front.

The cooling of the rear portion of the heater will permit it to be positioned any place in a room, since under no circumstances will the back of the heater become 65 sufficiently heated to increase the fire hazard

or cause possible damage to woodwork in or about a room.

It is not my intention to limit the invention to the precise details of construction shown in the drawings, it being apparent 70 that such may be varied without departing from the spirit and scope of the invention.

Having described the invention, what I claim as new and desire to have protected by Letters Patent, is:—

75 1. A gas heater embodying therein a reflecting casing having an opening substantially centrally thereof, whereby a reflecting surface is presented about and in front of said opening, means forming a combustion chamber rearwardly of said opening, a heating unit within said combustion chamber and exposed through said opening, and means forming a flue, the opposite ends of which communicate respectively with atmosphere adjacent the lower part of, and above, said combustion chamber, whereby a convection movement of air is set up about said combustion chamber and air so heated is delivered to a room.

80 85 90 95 100 105 2. A gas heater embodying therein a reflecting casing having an opening substantially centrally thereof, whereby a reflecting surface is presented about and in front of said opening, an open topped housing forming a combustion chamber rearwardly of said opening, a heating unit within said combustion chamber and exposed through said opening, and means forming a flue inclosing said housing and having its opposite ends respectively in communication with atmosphere adjacent the lower part of, and above, said combustion chamber, and communicating therewith through the open top thereof, whereby a convection movement of air is set up about said combustion chamber and air so heated is delivered to a room.

110 115 120 3. A gas heater embodying therein a casing in the form of a reflector and having an opening substantially centrally thereof, whereby a reflecting surface is presented about and in front of said opening, means forming a combustion chamber rearwardly of said opening, a heating unit within said combustion chamber and exposed through said opening, and means forming a flue, the opposite ends of which communicate respectively with atmosphere adjacent the lower part of, and above, said combustion chamber, whereby a convection movement of air is set up about said combustion chamber and air so heated is delivered to a room.

125 4. A gas heater embodying therein a reflecting casing having an opening substantially centrally thereof, whereby a reflecting surface is presented about and in front of said opening, an open topped housing forming a combustion chamber rearwardly of said opening, a heating unit within said combustion chamber and exposed through

- said opening, and means forming a flue inclosing said housing and having its opposite ends respectively in communication with atmosphere adjacent the lower part of, and above, said combustion chamber, and communicating therewith through the open top thereof, whereby a convection movement of air is set up about said combustion chamber and air so heated is delivered to a room, said flue being substantially parallel with the back wall of said housing and extending across the top of said combustion chamber and opening above and forwardly of said casing.
15. 5. A gas heater embodying therein a reflecting casing having an opening substantially centrally thereof, whereby a reflecting surface is presented about and in front of said opening, an open topped housing forming a combustion chamber rearwardly of said opening, a heating unit within said combustion chamber and exposed through said opening, said heating unit comprising a burner casing having a plurality of burner openings adapted to develop a blue flame, and a refractory element positioned above each burner opening, and means forming a flue inclosing said housing and having its opposite ends respectively in communication with atmosphere adjacent the lower part of, and above, said combustion chamber, and communicating therewith through the open top thereof, whereby a convection movement of air is set up about said combustion chamber and air so heated is delivered to a room.
30. 6. A gas heater embodying therein a reflecting casing having an opening substantially centrally thereof, whereby a reflecting surface is presented about and in front of said opening, an open topped housing forming a combustion chamber rearwardly of said opening, a heating unit within said combustion chamber and exposed through said opening, comprising a casing forming a mixing chamber and a distributing chamber communicating therewith through its entire length, said casing having a plurality of alined openings through the top and bottom thereof, the top openings being larger than the lower openings, a tube opening through the lower openings and extending into the upper openings respectively, whereby a burner opening is formed between each tube and the wall of the upper opening, and supplemental air is delivered within said opening, and mixing tube adapted to be placed in communication with a source of gas supply, and discharging directly into said distributing chamber, and means forming a flue inclosing said housing and having its opposite ends respectively in communication with atmosphere adjacent the lower part of, and above, said combustion chamber, and communicating therewith through the open top thereof, whereby a convection movement of air is set up about said combustion chamber and air so heated is delivered to a room, and a plate extending across the bottom of said combustion chamber adjacent the burner openings, and across the flue, the portion of said plate within said combustion chamber having means for retaining the refractory elements with relation to the burner openings and the portion thereof within the flue having openings therethrough and engaging the walls of said flue to stay same.
45. 7. A gas heater embodying therein a reflecting casing having an opening substantially centrally thereof, whereby a reflecting surface is presented about and in front of said opening, an open topped housing forming a combustion chamber rearwardly of said opening, a heating unit within said combustion chamber and exposed through said opening, comprising a casing forming a mixing chamber and a distributing chamber communicating therewith through its entire length, said casing having a plurality of alined openings through the top and bottom thereof, the top openings being larger than the lower openings, a tube opening through the lower openings and extending into the upper openings respectively, whereby a burner opening is formed between each tube and the wall of the upper opening, and supplemental air is delivered within said opening, and mixing tube adapted to be placed in communication with a source of gas supply, and discharging directly into said distributing chamber, and means forming a flue inclosing said housing and having its opposite ends respectively in communication with atmosphere adjacent the lower part of, and above, said combustion chamber, and communicating therewith through the open top thereof, whereby a convection movement of air is set up about said combustion chamber and air so heated is delivered to a room.
50. 8. A gas heater embodying therein a reflecting casing having an opening substantially centrally thereof, whereby a reflecting surface is presented about and in front of said opening, an open topped housing forming a combustion chamber rearwardly of said opening, a heating unit within said combustion chamber and exposed through said opening, comprising a casing forming a mixing chamber and a distributing chamber communicating therewith through its entire length, said casing having a plurality of alined openings through the top and bottom thereof, the top openings being larger than the lower openings, a tube opening through the lower openings and extending into the upper openings respectively, whereby a burner opening is formed between each tube and the wall of the upper opening, and supplemental air is delivered within said opening, and mixing tube adapted to be placed in communication with a source of gas supply, and discharging directly into said distributing chamber, and means forming a flue inclosing said housing and having its opposite ends respectively in communication with atmosphere adjacent the lower part of, and above, said combustion chamber, and communicating therewith through the open top thereof, whereby a convection movement of air is set up about said combustion chamber and air so heated is delivered to a room.
55. 9. A gas heater embodying therein a reflecting casing having an opening substantially centrally thereof, whereby a reflecting surface is presented about and in front of said opening, an open topped housing forming a combustion chamber rearwardly of said opening, a heating unit within said combustion chamber and exposed through said opening, comprising a casing forming a mixing chamber and a distributing chamber communicating therewith through its entire length, said casing having a plurality of alined openings through the top and bottom thereof, the top openings being larger than the lower openings, a tube opening through the lower openings and extending into the upper openings respectively, whereby a burner opening is formed between each tube and the wall of the upper opening, and supplemental air is delivered within said opening, and mixing tube adapted to be placed in communication with a source of gas supply, and discharging directly into said distributing chamber, and means forming a flue inclosing said housing and having its opposite ends respectively in communication with atmosphere adjacent the lower part of, and above, said combustion chamber, and communicating therewith through the open top thereof, whereby a convection movement of air is set up about said combustion chamber and air so heated is delivered to a room.
